(57) **CLAIM**

The ornamental design for a two-piece cap assembly for modular panel mounting systems design, as shown and described.

DESCRIPTION

FIG. 1 is an exploded environmental perspective view of a two-piece cap assembly for modular panel mounting systems in an exemplary environment;

FIG. 2 is an environmental assembled right elevation view thereof in an exemplary environment;

FIG. 3 is an environmental top perspective assembled view thereof;

FIG. 4 is an environmental exploded perspective view thereof in an exemplary environment;

FIG. 5 is an environmental top perspective assembled view thereof in an exemplary environment;

FIG. 6 is a frontal elevation view thereof;

FIG. 7 is a rear elevation view thereof; and,

FIG. 8 is a right elevation view thereof.

The broken lines showing environment in the drawings are included for illustrative purposes only and form no part of the claimed design. The outer broken line boundaries in Figures depicting the boundaries of the claimed design indicate that a specific shape forms no part of the claimed design.
